Attorney

scale of the double ladder when extended into straightened-out position, one ladder in extension of the other; and,

Fig. 6 is a perspective, on the same scale as Figs. 1 to 3, of the double ladder in folded position.

In the drawings, the two members or legs of the double ladder are designated by 11 and 12. The two members 11, 12 are joined together by hinges 13, 14. Each member or ladder comprises a series of U-shaped stirrups 15 and 16, respectively, each of the stirrups 15 constituted by a step 17 as a base and two lateral arms 19, 20 and each of the stirrups 16 by a step 18 and two lateral arms 21, 22. Arms 19, 20 are interconnected by links 24, 25 and arms 21, 22 by links 26, 27, respectively, and thus form side-structures of the ladder members.

The U-shaped stirrups and the links may be of any suitable material, such as sheet material, strips of iron, steel, brass, aluminum, or other metal, or wood or any other appropriate, also synthetic material. Reinforcement ribs may be provided such as shown at 30 on the surfaces of the links.

Pivots in the form of screw bolts, rivets, or the like, two on each end member and three on all others, are provided on the arms and links and disposed equidistantly spaced apart from one another for connecting the arms and links to side-structures at both sides of the ladder. More specifically, the links 24, 25 and 26, 27 are pivotally connected by means of pivots 31 at one of their ends, the upper end, with one end, the step-end or front end, of the arm of one of the U-shaped stirrups; by means of pivots 32 at a median point with a median point of the arm of the subsequent stirrup, and by means of pivots 33 at the other, the lower end with the upper or rear end of the arm of the next succeeding U-shaped stirrup. Arms and links thus constitute with their pivots, the side-structures of the ladder in the form of collapsible and expandable rhomb mechanisms.

Each side-structure of the double ladder is provided at its foot end, at the end links 34 for instance, with a projection 35, constituting a broad supporting base for the respective side-structure of the ladder.

In the embodiment illustrated there is arranged between the lowermost links 34 and the appertaining arms 36 a locking device consisting in the example shown of an arched projection 37 of the links 34 with locking means, such as holes and pegs, screw bolts, pins, as generally indicated at 38, engaging the elements 34. By means of such or other locking devices, two adjacent elements of the rhomb mechanism may be connected in fixed angular relationship and the side-structures, when erected, thus be locked against undesired collapsing and expanding.

By means of these locking devices, adapted to be set in various locking positions and by selection of one of the holes 38 to be engaged with the arms 36, the mutual inclination of links and arms may be set. The distances between the steps may be varied and various lengths of the ladder obtained. An individual of the double ladder may so be adapted to various heights. The double ladder as illustrated in Figs. 1 and 2 may be employed with equal lengths of its members 11, 12, on a level floor, or, when as Fig. 4 illustrates the individual members 11, 12 are set at various lengths, on an inclined or uneven floor or on a staircase, or the like. The locking de-

vices 37, 38, of one member (12) are so set that this member is shorter than the other (11) and the different heights of the bearing surfaces are compensated. The lengths of the two members 5 will be so set that the members generally include the same angle with the vertical.

The two members 11, 12 of the double ladder are preferably hinged together by means of detachable bolts, generally indicated at 13, 14. When this joint is disconnected, each member 10 may be employed by itself as an independent unit and serve as a foldable simple ladder. On the other hand, the two members with their hinges joined, may be fully extended into straight position, one ladder (12) in extension of the other (11). A single ladder of double extension or length is thus obtained, as Fig. 5 illustrates. The two members 11 and 12 will then be locked individually by locking devices such as described with reference to elements 37, 38, and, similarly, in their position one against the other by locking means such as braces 30 which connect by means of detachable elements, such as screw bolts, thumb screws, or others, two elements such as links 41, 42, Fig. 5, one at each ladder, and adjacent to the hinges 13, 14, in fixed angular relationship so that both ladders 11, 12 are locked in extended straight position, one ladder in extension of the other.

If the ladder is to be folded together into the position shown on Fig. 6, the locking devices 37, 38 are unlocked, all members of the ladder are released and may now collapse, the arms 19, 20 and 21, 22 and links 24, 25 and 26, 27 being pivoted about their pivots 31, 32, 33, until the U-shaped stirrups and the links lie close together, as Fig. 6 illustrates. In order to reduce as far as possible the dimensions of the folded ladder, in accordance with the invention, the steps 17 of the U-shaped stirrups of one of the ladders (11) are of a width and the appertaining arms 19, 20 of a length greater than those of the steps 18 and the arms 21, 22 of the other ladder 12, thus sufficient, when the stirrups 15 and links 24, 25 are folded together, to accommodate in the space confined on three sides by the juxtaposed stirrups 15, of one ladder, 11, the links 26, 27 and stirrups 16 of the other ladder, 12, when likewise folded together. Conveniently, the ladders are so joined by the hinges 13, 14 that the steps of at least the wider ladder are directed to the outside. Otherwise, the ladders when to be folded together, are to be turned one over the other at their common hinges 13, 14.

I claim:

A double ladder consisting of a pair of foldable ladders each of the type which comprises a pair of side structures each composed of arms and links and with pivots disposed on said arms and links for connecting said arms and links at points equidistantly spaced apart from one another, said links being pivotally connected, by means of said pivots, at one of their ends with one end of one of said arms, at a median point with a median point of the subsequent arm, and at the other end with the other end of the next succeeding arm, arm and link sections between and with their pivots thus forming collapsible and expandable rhomb mechanisms; equally disposed arms of both side structures being integrally shaped as open U-shaped stirrups, the bases of the U-shaped stirrups interconnecting the side structures and forming the steps of the ladders; each of said side structures having a hinge for pivotally joining said ladders, the steps

of the U-shaped stirrups of one of said ladders being of a width and the appertaining arms of a length greater than those of the other of said ladders, thus sufficient, when said stirrups and said links are folded together, to accommodate in the space confined at three sides by the juxtaposed stirrups and links of the first of said ladders, the juxtaposed stirrups and links of the second of said ladders.
